DRYING HOUSE

Forrest H. Smith, Kinston, N. C.

Application July 12, 1930, Serial No. 467,542

7 Claims. (Cl. 34—19)

This invention relates to new and useful improvements in drying houses which are particularly adapted for use in drying or curing tobacco, and embodies certain improvements over 5 my co-pending application Serial No. 383,994, filed August 7, 1929, which has matured into Patent 1,811,980, of June 30, 1931.

Among the various objects of my invention are to provide one or more burners within the drying 10 house and so arranged that the air within the house will be directly heated by said burner or burners; to arrange the burner or burners adjacent the floor or ground within the house and to provide a baffle thereabove which will prevent the 15 flame from passing upwardly in a straight line, which will permit the heated air to be deflected from the burner, and which baffle will also function to guard the burner against tobacco leaves and sand dropping into said burner; to provide a plurality of burners within the drying house 20 and to connect said burners by a common oil feeding pipe which is connected to a main oil supply located outside of the house; to locate the burners within the house and adjacent the walls 25 thereof and to provide adjustable openings in the walls for the admission of atmospheric air to the burners; to provide air inlets to the burners which terminate at points above the burners whereby the inlet of air will not affect the 30 operation of the burner; to provide a vertically adjustable main oil supply to thereby vary the oil level in the burners and consequently vary the temperature within the house; to provide means automatically responsive to temperature changes 35 within the house to raise and lower the main oil supply; to provide a burner or burners within the house and to associate a vertically adjustable conduit with the burner or burners whereby the conduit may be lowered to receive the burners or may be suspended in spaced relation; to 40 provide the individual burners with a hood surrounding the combustion chamber, the hood having a top spaced from the body portion to provide an air passage and an adjustable air guard 45 mounted for movement along said air passage, and to provide a plurality of burners within the house and located respectively in individual boxes or chambers and to directly connect said chambers with a heat radiating conduit located within the house.

With these and other objects in view which will more fully appear, the nature of the invention will be more clearly understood by following the description, the appended claims, and the

several views illustrated in the accompanying drawings.

In the accompanying drawings which show several modifications of my invention,

Figure 1 is a horizontal section through a 5 drying house showing a plurality of connected burners disposed therein and connected to a main oil supply,

Figure 2 is a vertical sectional view taken on the line 2—2 of Figure 1, 10

Figure 3 is a detailed vertical sectional view showing the form of air inlet disclosed in Figures 1 and 2,

Figure 4 is a vertical sectional view showing a 15 modified form of air inlet,

Figure 5 is an enlarged vertical sectional view of the main oil supply tank and support,

Figure 6 is an enlarged vertical sectional view through one of the burners and showing the baffle plate arranged thereabove together with 20 the supports for said plate,

Figure 7 is a detailed horizontal sectional view taken through the burner,

Figure 8 is a partial elevation showing the hood of a burner, a top therefor, together with 25 an adjustable air shield,

Figure 9 is a top plan view of the structure shown in Figure 8,

Figure 10 is a modified form of baffle plate 30 which may be used with an individual burner,

Figure 11 is another form of baffle plate which may be used with an individual burner,

Figures 12, 13, and 14 are fragmentary perspective views showing modified forms of baffle plates which may be associated with a series of 35 burners,

Figure 15 is a horizontal sectional view through a house showing an air conduit directly connected to a plurality of boxes or chambers containing individual burners, 40

Figure 16 is a side elevation showing two burners, two burner chambers and the directly connected air conduit, as shown in Figure 15,

Figure 17 is a horizontal sectional view taken 45 through the structure shown in Figure 16,

Figure 18 is a transverse sectional view taken on the line 18—18 of Figure 16,

Figure 19 is a detailed view showing a burner and an air conduit supported thereabove and 50 adapted to be lowered close to the burner or to a position to receive the burner,

Figure 20 is a view similar to Figure 15 but showing a single burner and burner chamber connected to the conduit,

Figure 21 is a detailed sectional view taken on the line 21—21 of Figure 2, and

Figure 22 is a view similar to Figure 2 but showing means responsive to temperature changes 5 in the house for automatically raising and lowering the main oil supply.

Referring particularly to Figures 1, 2, 3, 6, 7, and 21, I have illustrated one form of my invention in which a plurality of burners are arranged 10 within the drying house at a common level and are connected in series with an oil feed pipe which in turn is connected to a main oil supply tank which is adapted to be manually adjustable vertically and retained in an adjusted position to 15 thereby vary the oil level in all of the burners simultaneously whenever it becomes desirable to vary the temperature within the house. Referring particularly to these figures, there is shown a drying house A having side walls 5, 5 and 20 end walls 6, 6. Located within the house and disposed adjacent the walls 5 and 6 is a plurality of burner units B, the burners along each wall being arranged in a series alignment. Although I have shown three burners in each series, it will 25 be understood that any number of burners may be employed without departing from the spirit of my invention. An additional series of burners B are arranged in alignment and extend across the central part of the house. An oil feed pipe 7 connects the wall burners in series and an oil pipe 8 is connected to the pipe 7 and to the centrally located burners. Each burner is supported from the pipe 7 or 8 through the medium of an upstanding pipe 9 which receives the lower end of 30 a vertical pipe 10. A packing gland 11 is carried by the pipe 9 for sealing the joint between the pipe 9 and the pipe 10. The upper end of the pipe 10 is integral with a bowl 12 and has communication therewith through an opening 13. 35 The bowl 12 is annular in plan view and is U-shaped in cross section to form a resultant chamber 14 for receiving the wick 15 and the oil which is fed from the main oil supply. It will be noted that the oil level in the chamber 14 will 40 normally correspond with the oil level in the main supply tank; that if the main supply tank is raised or lowered the oil level in the chamber 14 will correspond, and that if the burner including the chamber 14 be raised above the oil level in the 45 main supply tank, the burner will cease to operate. Seated upon the bowl are inner and outer perforated cylinders 16 and 17 forming therebetween a combustion chamber which registers with the wick 15. Disposed around and in spaced relation 50 to the outer cylinder 17 is an imperforate hood 18 which is connected to the cylinders 16 and 17 by a cross rod 19. Another cross rod 20 arranged at an angle to the cross rod 19 passes through the two cylinders 16 and 17 and the hood 18 and 55 operates with the rod 19 to support the hood 18 and to prevent relative rotation between the cylinders and the hood. Rigidly secured to the bowl 12 and extending downwardly therefrom is a rack bar 21 which is engaged by a pinion 22 60 fixed on a shaft 23 journaled on a support 24 which extends upwardly and is fixedly connected to the oil feed pipe 7. A hand wheel 25 is fixed to the shaft 23. Thus when the hand wheel is turned the pinion 22 will raise or lower the rack bar 21 and consequently the burner with the result that the chamber 14 may be elevated above the oil level in the main supply tank and thereby 65 cause said burner to cease functioning.

The pipes 7 and 8 may be supported above the 70 ground by any suitable means, as for instance

supporting blocks 26. Disposed above each burner B and in spaced relation thereto is a baffle plate 27, said plate being supported by legs 28, 28. This plate includes an imperforate central portion 29 which is disposed directly above the burner, and a series of perforations 30 which surround the imperforate portion 29 and through which the heated air from the burner may pass upwardly. In practice, I may desire to support a relatively long and narrow screen 31 above each 10 of the several series of burners, the screen being supported by the walls of the house. The screens are arranged directly below the tobacco which is in turn supported by tier poles 32 located above said screens. Thus the baffle plates 27 prevent 15 the flames from the burners passing upwardly into direct contact with the tobacco and thereby all danger of the burners setting the tobacco leaves on fire is avoided. Furthermore the imperforate portion 29 of each baffle plate prevents 20 any loose leaves or sand from gravitating into the burners, and the perforations 30 in each baffle plate permit the heated air to pass upwardly from the burners into direct contact with the tobacco leaves. In order to provide for a proper 25 circulation of air within the house, I have provided each wall of the house with an air inlet opening 33 adjacent the bottom thereof, and within the house I have provided a baffle plate 34 which parallels the wall and extends upwardly to 30 a point above the burners so as to permit the atmospheric air to enter the house without impairing the operation of the burners. A single oil inlet pipe 35 extends through one wall 5 of the 35 house and has its inner end connected to the adjacent feed pipe 7. This inlet pipe 35 terminates at its upper end in an upstanding pipe section and to the upper end of this pipe section is connected a bowl shaped support 37 which communicates with said pipe 36 as shown in Figure 5. 40 Seated upon the annular wall 38 of said bowl 37 is a main oil supply tank 39 having a valved outlet 40 at its lower end. When the tank 39 is placed on the support 37 the oil therefrom will pass through the valved outlet 40 into the support 45 and thence through the pipe section 36 to the inlet pipe 35 and thence to the feed pipes 7 and 8. When the pipe system is filled the oil within the support 37 will seal the valved outlet 40 as will be readily understood. 50

I have found in practice that the temperature within the house should be maintained between 90° F. and 180° F. When the temperature in the house approaches the minimum, the main oil supply is elevated so as to raise the oil level in each 55 of the burner chambers 14, and when the maximum temperature in the house has been reached the main oil supply is lowered thus correspondingly lowering the oil level in each of the burner chambers 14. To this end I have provided means 60 for supporting the inlet pipe 35 and consequently the main oil supply tank 39 in different positions of vertical adjustment. For this purpose I have provided a U-shaped bracket 41 which receives the pipe 35 and which is suitably anchored in 65 the ground by a pin 42 or the like. The arms 43, 43 of this bracket are provided with alined openings arranged in vertical series. A stop pin 44 is permanently located within the upper alined openings and functions to limit the upper 70 movement of the inlet pipe 35. A second stop pin 45 is adapted to be positioned in any of the other alined openings so as to support the inlet pipe 35 together with the main oil supply tank 39 in any 75 predetermined position of vertical adjustment.

Instead of employing the air inlet baffles 34 I may prefer to employ an inlet pipe 46 as shown in Figure 4. This inlet pipe 46 has its inlet end disposed in registration with an opening 47 formed in the wall 5 of the house and is provided with a supporting flange 48 which is secured to said wall by screws or bolts. This pipe 46 extends inwardly for any predetermined distance and then terminates in an upwardly extending portion or end section 49. By this arrangement the fresh air will be directed into the central portion of the house.

Instead of employing a flat baffle plate 27 and supporting legs 28 as shown in Figures 1, 2, and 15 particularly, I may desire to employ a dome shaped baffle plate 50 as shown in Figure 11. This plate 50 is provided with an imperforate top portion and with a perforate wall. The wall is provided with upwardly extending recesses 51, 51 to receive the feed pipe 7.

Instead of employing individual baffle plates such as 27 and 50, I may prefer to employ a relatively long and narrow baffle plate which may cooperate with a plurality of burners. In Figures 25 12, 13, and 14, I have shown three modified constructions of these relatively long and narrow baffle plates. In Figure 12 the baffle plate 52 is arcuate in cross section, whereas in Figure 13 the baffle plate 53 is flat, and whereas in Figure 14 the baffle plate 54 is similar to the baffle plate 52 but is provided with flat inclined sides.

Instead of employing any of the baffle plates 27, 50, 52, 53, or 54, I may prefer to mount a baffle plate 55 as shown in Figure 8 on the hood 18 of each burner. The baffle plate 55 is cone shaped and is supported on the annular flange 18^a of the hood 18 through the medium of spaced uprights 56, thus forming an annular air passage between the hood 18 and the baffle plate 55. In order to avoid the burner being disturbed by air currents, I provide an air guard 57 which extends partially around the air space between the baffle plate 55 and the hood 18. This guard 57 is supported from a pin 58 extending upwardly from the apex of the cone shaped baffle plate 55 through the medium of a supporting wire 59 which permits the guard plate 57 to be rotated to any predetermined position.

I have shown a modified form of my invention in Figures 15, 16, 17, and 18. In this form, I have enclosed the burners B in boxes or chambers 60 and have connected these chambers by T-couplings 61 to a conduit 62 which extends around the house in parallelism with the walls 5 and 6 thereof. A cross conduit 63 connects opposite side portions of the conduit 62 and this cross conduit is connected in the same manner to the centrally located burners. Each of the boxes 60 is placed directly against the associated wall of the house and the wall is provided with an opening 64 for admitting outside air into said box. The opening 64 is adjustable in size by means of a sliding door 65. The heated air from the various burners is received into the conduit 62 and across the conduit 63 and this air passes outwardly to the atmosphere through an outlet pipe or conduit 66. Thus in this form of my invention, the smoke together with the air which is directly heated from the burners is not admitted into the house but is passed through the conduits 62 and 63 and thence outwardly to the atmosphere. Therefore the interior of the house is free from the products of combustion, although the conduits 62 and 63 are of sufficient area to

radiate sufficient heat for properly curing the tobacco within the house.

In Figure 20, I have illustrated substantially the same arrangement as shown in Figures 15-18, but have employed a single burner and a single burner chamber 67 instead of a plurality of burners and chambers. In this form I have provided an air inlet pipe 68 which communicates with the chamber 67 and an air outlet pipe 69 which communicates with the conduits 62^a and 63^a. 10

In the modification shown in Figure 19 there is disclosed a burner B and directly above this burner is located a conduit 70 having a downwardly extending inlet pipe 71 of an area sufficient to embrace the burner B. This conduit 70 is adapted to be supported for vertical adjustment by a wire 72 from some fixed point within the house whereby the conduit and the inlet pipe may be positioned above and in spaced relation to the burner B or may be lowered so as to position the 20 inlet pipe 71 directly around the burner.

It may be desirable to automatically raise and lower the main fuel supply tank 39 whenever the temperature changes within the house to any appreciable degree. To this end, I have pivoted the oil inlet pipe 35 centrally between its ends on a bracket 73 and have inserted a flexible coupling 74 in said inlet pipe 35 at a point between the bracket 73 and the house. The outer end of the inlet pipe 35 is rigidly connected to the oil supply tank 39, and in order to avoid repeated refillings of the tank 39, I preferably connect the upper end thereof by a flexible hose coupling 75 with the lower end of a stationary oil drum 76 of large capacity. The pivoted inlet pipe 35 is in the nature 25 of a lever and a counterweight 77 is mounted on the end of said inlet pipe 35 opposite the tank 39. Fixed to the inlet pipe 35 between the bracket 73 and the tank 39 are upper and lower armatures 78 and 79 respectively and associated with said 40 armatures are electromagnets 80 and 81 respectively. The magnet 81 is connected to a thermostat 82, which is located within the house, through the medium of a circuit 83 which includes any source of electrical energy such as batteries 84. 45 The magnet 81 is likewise connected to the thermostat 82 but through the medium of a circuit 85 which includes any source of electrical energy such as batteries 86. Thus when the temperature in the house is at minimum the circuit 83 will be automatically closed and the magnet 80 energized. As a result the tank 39 will be elevated and the oil level in the burner compartments 14 will be raised. This will cause the burners to generate increased heat and when the temperature 55 in the house reaches a maximum the thermostat 82 will automatically close the circuit 85 and energize the magnet 81 to lower the tank 39 and thereby lower the oil level in the chambers 14 of the burners. It will be understood that the 60 thermostat 82 includes adjustable contact arms 87, 88 and a temperature control arm 89 whereby the thermostat may be manually set for predetermined minimum and maximum temperatures.

It is of course to be understood that the details 65 of structure and arrangements of parts may be variously changed and modified without departing from the spirit and scope of my invention.

I claim:

1. The combination with a drying house including side walls and end walls, of a plurality of spaced independent fuel burning heating units located within the house and arranged in series adjacent the walls thereof, a main fuel supply located exteriorly of the house, a fuel feed pipe 75

- located inside the house and connecting all of the units, and a single inlet pipe connecting the main fuel supply and the fuel feed pipe.
2. The combination with a drying house including side walls and end walls, of a plurality of spaced independent fuel burning heating units located within the house and arranged in series extending substantially around and adjacent the walls thereof, means located above the units for supporting articles to be dried, spaced baffle means interposed between the units and the articles, and a screen interposed between the baffle means and the articles.
3. The combination with a drying house including side walls and end walls, of a plurality of fuel burning heating units located within the house and arranged in series extending around adjacent to the walls thereof, an individual imperforate boxing surrounding each unit, a conduit extending along the walls of the house and connected to the respective boxings, each boxing having an air inlet, and an air outlet connected to the conduit and exhausting into the atmosphere outside the house.
4. The combination with a drying house, of a heating unit therein, and a vertically adjustable hot air receiving conduit supported above the unit, said conduit having a depending inlet pipe disposed above the unit and of a size to surround the latter when the conduit is lowered.
5. The combination with a drying house, of a fuel burning heating unit located within the house, a vertically movable fuel supply tank located exteriorly of the house, a pipe connection between the tank and the unit, and means responsive to temperature changes within the house for automatically raising or lowering said tank to vary the fuel level in the heating unit.
6. The combination with a drying house, of a fuel burning heating unit located within the house, a vertically movable fuel supply tank located exteriorly of the house, a stationary main fuel supply tank located exteriorly of the house, a vertically movable fuel tank located exteriorly of the house, a flexible pipe connection between said tanks, a pipe connection between the vertically movable tank and the heating unit, and means responsive to temperature changes within the house for automatically raising or lowering said tank to vary the fuel level in the heating unit.
7. The combination with a drying house including side walls and end walls, of a plurality of spaced independent fuel burning heating units located within the house and arranged in series extending substantially around and adjacent the walls thereof, means located above the units for supporting articles to be dried, and spaced baffle means interposed between certain of said heating units and the article supporting means, the baffle means comprising imperforate portions disposed directly above the associated burners and perforated portions disposed at the sides of said imperforate portions.

FORREST H. SMITH.
